UNITED STATES PATENT OFFICE

HERBERT M. STURGIS, OF KANSAS CITY, MISSOURI, ASSIGNOR, BY MESNE ASSIGNMENTS, TO LEIGH HUNT, OF KANSAS CITY, MISSOURI

MOP HEAD

Application filed May 1, 1929. Serial No. 359,436.

This invention relates to mop heads and particularly to that class in which the handle is mounted for oscillation to either side of the mop so that both sides of the mop 5 may be selectively used.

The principal object of this invention is the provision of a mop head comprising a substantially flat frame having an inner member and an outer member, the outer 10 member being adapted to securely hold the mop material and having a three-point attachment to said inner member.

Another object of the present invention is the provision of a mop head comprising an 15 inner frame and an outer frame, the outer frame being formed of a plurality of strands of wire twisted around each other and having mop material secured between said strands by the twisting thereof, said outer 20 frame being connected adjacent its ends to said inner frame, and having a bar attached to one strand of said twisted outer frame and to said inner frame.

Other objects are simplicity, cheapness, 25 and rigidity of construction.

With these general objects in view as well as minor objects which will appear during the course of the detailed specification, reference will now be made to the accompanying 30 drawing in which:

Figure 1, is a plan view of a mop having a head embodying this invention;

Fig. 2, is an enlarged plan view of the mop 35 head with the mop material omitted;

Fig. 3, is a vertical section taken on line III—III of Fig. 2;

Fig. 4, is a fragmentary cross-sectional view taken on line IV—IV of Fig. 2;

Fig. 5, is a detached view of a portion of 40 the inner frame.

Like reference characters designate like parts throughout the several views and the numeral 10 designates an inner frame formed of a single piece of sheet metal or of separate parts as shown, to which the handle receiving member 11 is hingedly mounted at 45 12. Handle receiving member 11 as shown, comprises a formed sheet metal hinged portion 13 which is folded back upon itself and onto a cylindrical knurled sleeve 14. When

so positioned, a tapered socket member 15 is securely pressed over member 13 thus binding all parts of the handle receiving member in fixed relation. Handle 16 is adapted to frictionally engage in socket 15 55 and is removable therefrom.

Inner frame 10 is preferably rectangular in form and made of a wire 17 onto which is securely pressed a sheet metal member 18 having oppositely disposed open sockets 19 positioned adjacent opposite sides of said rectangular member. Extending forwardly and substantially parallel with sockets 19 is a bar 20 preferably integral with member 18. An outer frame 21 formed of a plurality of strands of wire 22 twisted around each other and having mop material 24 secured between said strands by the twisting thereof, is spaced apart from said inner frame, looped therearound and provided with spaced apart inwardly extending arms 23 adapted to be secured adjacent their extremities in sockets 19 by pressing said open sockets tightly against the twisted wires. It will be noted that the mop material does not extend to the inner ends of arms 23 but is spaced apart therefrom thus permitting the insertion of frame 21 in the sockets. Bar 20 extends forwardly and is secured at its outer end to the inner strand of the twisted wire frame 21, thus maintaining a smooth outer surface of the frame 21 and supporting the parts in a fixed relation. 75

Bar 20 is provided with a strengthening rib 25 which is formed therein. The bay 26 formed between the two parallel arms 23 is of sufficient width to allow the free movement of the handle receiving member 11 to either side of the mop thus making it possible to reverse the mop so that either side may be 80 used for the mopping operation. 85

The inner frame 10 may be made of a single piece of material and changed considerably in form without departing from the invention. 95

The mop head is constructed with its parts disposed substantially in the same plane and when the mop material is in position, is effectively covered with no parts protruding that might damage the furniture, etc. 100

I do not wish to limit this invention to the structure shown and described since many modifications may be made within the scope of the appended claims without departing from the spirit thereof.

5 What I claim is:

1. A mop head comprising an inner frame, a looped wire outer frame encompassing said inner frame with its front portion spaced apart from said inner frame and having spaced apart inwardly extending parallel arms secured to said inner frame, and an outwardly extending bar carried by said inner frame and secured at its outer end to said looped wire frame.
- 10 2. A mop head comprising a looped outer frame adapted to receive mop material and having spaced apart inwardly extending arms, an inner frame having sockets through which said arms extend, a bar connecting said inner frame to said outer frame adjacent its forward portion, and a handle pivotally connected with said inner frame and adapted to be moved between said inwardly extending arms.
- 15 3. A mop head comprising an inner frame, a looped outer frame formed of a plurality of strands of wire twisted around each other and having mop material secured between said strands by the twisting thereof, said outer frame having inwardly extending arms secured to said inner frame, and a bar secured at one of its ends adjacent the forward portion of said outer frame to one strand of wire thereof and at its other end to said inner frame.
- 20 4. A mop head comprising an inner frame, a looped wire outer frame having spaced apart inwardly and forwardly extending arms secured to said inner frame, a handle pivotably connected to said inner frame, and a bar positioned on a line extending between and parallel to said arms to secure said inner frame to the forward portion of said outer frame.

45 In testimony whereof, I hereunto affix my signature.

HERBERT M. STURGIS.
